(57) **CLAIM**

The ornamental design for an outdoor light as shown and described.

DESCRIPTION

FIG. 1 is a front-top-right perspective view of a first embodiment of an outdoor light showing our new design;

FIG. 2 is a rear-top-left perspective view thereof;

FIG. 3 is a front elevation view thereof;

FIG. 4 is a rear elevation view thereof;

FIG. 5 is a right side elevation view thereof;

FIG. 6 is a left side view thereof;

FIG. 7 is a top plan view thereof;

FIG. 8 is a bottom plan view thereof;

FIG. 9 is a front-top-right perspective view of a second embodiment of an outdoor light;

FIG. 10 is a rear-top-left perspective view thereof;

FIG. 11 is a front elevation view thereof;

FIG. 12 is a rear elevation view thereof;

FIG. 13 is a right side elevation view thereof;

FIG. 14 is a left side view thereof;

FIG. 15 is a top plan view thereof; and,

FIG. 16 is a bottom plan view thereof.

The broken lines in the figures illustrate portions of the outdoor light that form no part of the claimed design.
